Primary Examiner — John Windmuller*Assistant Examiner* — John R Yeh(74) *Attorney, Agent, or Firm* — Stevenson IP, LLC(57) **CLAIM**

The ornamental design for a shower wall mounted back and body washer, as shown and described.

DESCRIPTION

FIG. 1 is a front elevation view of a shower wall mounted back and body washer showing my new design with a pad separated therefrom for clarity;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is an isometric view thereof.

The broken lines in the figures show environment of the design that forms no part of the claimed design.

The broken away symbols indicate that no part of the hoses beyond what is shown form part of the claimed design.

1 Claim, 5 Drawing Sheets(56)
